UNITED STATES PATENT OFFICE.

CHARLES D. WRIGHT, OF ADRIAN, MICHIGAN.

GAS-LAMP.

1,134,935.

Specification of Letters Patent.

Patented Apr. 6, 1915.

Application filed April 16, 1914. Serial No. 832,174.

To all whom it may concern:

Be it known that I, CHARLES D. WRIGHT, a citizen of the United States, residing at the city of Adrian, in the county of Lenawee and State of Michigan, have invented 5 certain new and useful Improvements in Gas-Lamps, of which the following is a specification.

This invention relates to improvements 10 in gas lamps, and particularly to the inverted incandescent variety, and it consists in certain peculiarities of the construction, 15 novel arrangement and operation of the various parts thereof as will be hereinafter more fully set forth and specifically claimed.

The principal object of the invention is 20 to provide an inverted gas light or lamp which, while it is more especially intended for outdoor use, yet can be otherwise employed, and will be simple and inexpensive in construction, strong, durable and efficient in operation, and so made as to provide means for the mixture with the supply 25 of gas, of pure fresh air, thus obviating the liability of the discharged burnt gas mixing therewith when supplied to the mixer of the lamp.

A further and important object of the invention is to provide a gas lamp of such 30 construction that a single depending mantle or a plurality or group of depending mantles can be employed therewith and readily changed, one for the other, when 35 desired.

Another object is to provide means for 40 turning the supply of gas on or shutting it off without causing undue vibration or jars to the lamp and mantle or mantles carried thereby.

A still further object is to provide means 45 for supporting a globe around the burner in such a manner that said globe can be easily placed in position or removed and opened only at its upper portion.

Other objects and advantages of the invention will be disclosed in the subjoined description and explanation.

In the accompanying drawings, which 50 serve to illustrate the invention—Figure 1 is a central sectional view of a lamp embodying the improvements, but showing the burner tip and mantle or mantles omitted, and illustrating a part only of the 55 globe; Fig. 2 is a bottom plan view of the lamp with the globe removed; Fig. 3 is a

view in side elevation, looking in a different direction from that shown in Fig. 1, and illustrating the globe holder released from its normal position; Fig. 4 is a central sectional view of the mixer showing a modification in its construction and illustrating it equipped with a burner tip for a group or plurality of mantles, and Fig. 5 is a bottom plan view thereof.

Like numerals of reference refer to corresponding parts throughout the different views of the drawings.

The reference numeral 10 designates the casing of the lamp, which is preferably made of metal and substantially bell-shaped, as shown in Figs. 1 and 3 of the drawings. This casing is open at its top and bottom and is provided in its wall near its upper portion with openings 11 and 12 for the reception of portions of the mixer, as will be presently explained. Fastened to the inner upper portion of the casing 10 is a spider 13, which is provided with a central opening, in which is located an externally screw threaded nipple or coupling 14, which engages at its upper portion the lower end of a gas supply pipe 15, by means of which the lamp is suspended, and through which pipe gas is supplied to the mixer and burner. Secured to the lower portion of the coupling 14 is the upper part of the mixer which is designated as a whole by the reference numeral 16, the upper end of which rests against the lower surface of the central portion of the spider 13, on the upper surface of which is mounted a cup-shaped deflector 17, which is held in contact with the spider 13 by means of a washer 18 surrounding the coupling 14 and interposed between the lower end of the pipe 15 and said deflector.

As is clearly shown in Figs. 1 and 4, the mixer 16 is provided near its upper end with a laterally extended tube 19, and below the same with a floor or partition 20, which stops the downward flow of gas and causes it to pass outwardly through the tube 19, which is secured at its outer end to the upper portion of a valve casing 21 in which is seated a rotary valve 22, the stem 23 of which is provided with a transverse opening to receive an arm 24 or extension on the valve operating rod 25, which is provided at its lower end with a handle 26 to be used for turning the valve 22 so as to turn on or shut off the supply of gas. The valve 22 is pro-

vided with a port 27, which extends longitudinally in said valve and then outwardly through one side thereof to register with an opening 28 in a nozzle 29, which is connected 5 to a screw threaded nipple 30 on the valve casing 21, and extends to near the outer end of the mixing tube 31, which communicates with the body of the mixer 16 just below the floor 20 thereof. The nozzle 29 is provided 10 with a guard 32 which has openings 33 for the intake of air which is mingled with the gas as it passes through the opening 34 of the guard or cap 32 and into the tube 31 of the mixer. The tubes 19 and 31 of the 15 mixer are extended through the openings 11 and 12 respectively of the casing 10, so that the mixture of gas and air will take place externally of the casing 10, thus precluding any possibility of the discharged burnt gases 20 being mixed with the supply of gas. Secured to the lower portion of the mixer 16 is a coupling 35 to which is secured a tube 36 which is provided with a strainer 37 just below the coupling 35 for breaking up the 25 mixture of air and gas and for catching any foreign substances that may be borne thereby. A suitable burner tip (not shown) carrying one or more mantles can be secured to the tube 36, as is apparent, thus enabling the 30 lamp to be equipped with a single mantle burner or a burner having a group of mantles as may be desired. Horizontally located on the tube 36 is a disk 38 which has a series of radially arranged blades 39 35 pitched at angles, as shown in Fig. 1 of the drawings. This disk and the blades thereof are employed to facilitate the draft through the inner casing 40 which surrounds the mixer 16 and tube 36, and is secured at its 40 upper portion to the upper inner portion of the casing 10, yet in such a manner that it will be spaced from said casing at the lower portion of the latter.

Secured to the lower part of the casing 10 45 by means of a hinge 41 is a globe holder or carrier 42, which is provided with a number of set screws 43, to be used for clamping the upper portion of the globe 44, which fits in the ring-like holder 42, as is clearly shown in 50 Fig. 1 of the drawings. The lower part of the casing 10 is provided at suitable points with slots 45 to receive the set screws 43 when the holder 42 is raised to its normal position, in which position it may be retained by means of a catch 46 pivotally secured at its upper end to the casing 10, and depending at its other end to the lower portion 55 of the casing.

In Figs. 4 and 5 of the drawings is shown 60 a modification in the manner of connecting the mantle carrying burners to the mixer 16, which consists in dispensing with the coupling 35 and tube 36 and screwing the upper

portion 47 of a group mantle carrier 48 directly into the lower portion of said mixer. 65 It is obvious that a single mantle carrier can be thus secured into the lower portion of the mixer 16 instead of the group carrier which, as before stated, can also be done when the construction shown in Fig. 1 and 70 above described is employed.

From the foregoing and by reference to the drawings, it will be understood and clearly seen that by employing my improvements the hydrocarbon or gas supplied 75 through the pipe 15 and mixer 16 will be commingled with fresh air drawn or forced into the outer end of the tube 31 by the jet of gas passing through the nozzle 29, and that such mixture will be free from burnt 80 charges of discharged gases, as the tube 31 receives its supply of the mixture of air and gas externally of the casing 10, thus affording an almost perfect combustible mixture. As the valve 22 is connected to the operating 85 rod 25, which may be detached therefrom if desired, it is obvious that said valve may be turned so as to regulate the supply of gas discharged through the nozzle 29 without the usual jar or vibration incident to the 90 pulling of chains ordinarily used for turning such valves, which jars or vibrations soon destroy the effectiveness of the mantles. It is further manifest that by the use of my improvements a lamp provided 95 with means for interchangeably connecting a single mantle burner tip or a group bearing mantle burner tip with the mixer of the lamp is furnished.

Having thus fully described my invention 100 what I claim as new and desire to secure by Letters Patent is—

In a gas lamp, the combination with a pipe for the supply of gas, of a mixer communicating therewith and depending therefrom, said mixer having a pair of laterally disposed conduits extended therefrom, one above the other, a partition in the mixer between said conduits, a vertically disposed valve casing connected at its upper portion 105 to the upper one of said conduits at the outer end thereof, a jet nozzle extended from said casing below the upper conduit and in alignment with the outer end of the lower conduit, an apertured guard surrounding the 110 discharging end of said nozzle and spaced from the free end of the lower conduit, a rotary valve in the lower portion of said valve casing to control the flow of gas from said casing through said nozzle, and a depending rod connected to said valve to turn 115 the same.

CHARLES D. WRIGHT.
